J. FRIERSON,
SCARFPIN GUARD,
APPLICATION FILED JUNE 11, 1920.

1,364,742.

Patented Jan. 4, 1921.

J. FRIERSON.
INVENTOR.

BY
A. Murphy, Jr., ATTORNEY.

UNITED STATES PATENT OFFICE.

JESSE FRIERSON, OF ATLANTIC CITY, NEW JERSEY.

SCARFPIN-GUARD.

1,364,742.

Specification of Letters Patent.

Patented Jan. 4, 1921.

Application filed June 11, 1920. Serial No. 388,319.

To all whom it may concern:

Be it known that I, JESSE FRIERSON, a citizen of the United States, residing at Atlantic City, in the county of Atlantic and State of New Jersey, have invented certain 5 new and useful Improvements in Scarfpin-Guards; and I do hereby declare the following to be a full, clear, and exact description of the invention, such as will enable others skilled in the art to which it appertains to 10 make and use the same.

This invention relates to new and useful improvements in scarf pin guards and has for its primary object the provision of a device of the above stated character, which will 15 prevent removal or loss of a pin from a scarf or tie and which may be easily and quickly removed from the pin.

Another object of this invention is the provision of means for preventing loss of the 20 guard and which will also hold the tie or scarf to the shirt.

A further object of this invention is the provision of a scarf pin guard of the above 25 stated character which will be simple, durable and efficient, and which may be manufactured and sold at a comparatively low cost.

With these and other objects in view as will become more apparent as the description 30 proceeds, the invention consists in certain novel features of construction, combination, and arrangement of parts as will be hereinafter more fully described and claimed.

For a complete understanding of my invention, reference is to be had to the following description and accompanying drawings, in which:—

Figure 1 is a view in elevation illustrating 40 the guard applied to a pin,

Fig. 2 is a vertical sectional view of the guard,

Fig. 3 is a plan view illustrating the spring clamp,

Fig. 4 is an end view illustrating the same,

Fig. 5 is a sectional view taken on the line 6—6 of Fig. 4.

Referring in detail to the drawing, the numeral 1 indicates as an entirety a guard

50 consisting of a tubular body 2 that has one end closed and has formed on its closed end an eye 3 to which a chain or flexible element 4 is connected. A suitable clasp 5 is secured to the free end of the chain or flexible element 4 and is adapted to secure a tie or scarf

to a shirt and to prevent loss of the body or guard.

A substantially U-shaped spring 6 is secured within the body and has its arms transversely curved with their concaved sides in opposing relation and said arms have their ends bent inwardly upon themselves to form gripping tongues 7 that lie in close proximity to each other and have grooves 8 formed in their opposing faces 65 adapted to receive and grip the pin when inserted in the body. The grooves terminate at one of their ends within the curved portion 9 or where the tongues 7 form on to the arms of the U-shaped spring so as to provide a mouth for guiding the end of the pin into the grooves. The gripping tongues 7 lie in close proximity to the open end of the body 2 and have grooves 8 in their opposing faces so that when a pin is inserted within 70 the open end of the body, the same will pass into the grooves 8 and be held therein by the tension of the tongues 7. A block 10 of cork or similar material is located between the arms wholly within the plane thereof and 75 has the ends adjacent the inner ends of the tongues spaced inwardly from said ends of the tongues and has its other end engaging the web portion of the spring. The sides of the block are convexed and received by the 80 concaved sides of the arms to hold the block in place. The block is adapted to receive the pointed end of the pin so as to protect the same. The open end of the body has formed thereon an inwardly directed flange which 85 engages the curved outer ends of the tongues to aid in holding the U-shaped spring in said body. It is to be understood that the body 2, flexible elements 4 and clasp 5 may be constructed from any metal suitable for the purpose while the spring 6 is constructed from a high grade flexible metal.

While I have shown and described the preferred embodiment of my invention, it will be understood that minor changes in construction, combination, and arrangement of parts may be made without departing from the spirit and scope of the invention, as claimed.

Having thus described my invention what 105 I claim is:

A scarf pin comprising an elongated spring of U-form having parallel arms transversely curved with their concaved sides in opposing relation, gripping tongues 110

extending inwardly from the free ends of the arms and having their outer ends curved laterally and formed integrally with the free ends of the arms, the tongues being arranged 5 in abutting relation and provided in their opposing sides with grooves adapted to receive a pin and extending into the curved outer ends of the tongues to provide a guide adapted to facilitate the insertion of the pin 10 between the tongues, a cork located between the arms wholly within the plane thereof and having the end adjacent the inner ends of the tongues spaced inwardly from said ends of the tongues and having its other end 15 engaging the web portion of the spring connecting the arms, the sides of the cork being

convexed and received by the concaved sides of the arms to hold the cork in place, a casing closed at one end in which the spring and cork are arranged, said web portion engaging the closed end of the casing and said arms engaging the side wall of the casing, and an inwardly directed flange at the open end of the casing and engaging the curved outer ends of the tongues. 20 25

In testimony whereof I affix my signature in presence of two witnesses.

JESSE FRIERSON.

Witnesses:

J. J. POTETE,
WILLIAM CLINE.
